No. 36,815.

Patented February 23, 1904.

UNITED STATES PATENT OFFICE.

JAMES MADDOCK, OF ALSAGER, ENGLAND, ASSIGNOR TO MADDOCK & MILLER, A CORPORATION OF NEW YORK.

DESIGN FOR A COVERED DISH.

SPECIFICATION forming part of Design No. 36,815, dated February 23, 1904.

Application filed January 20, 1904. Serial No. 189,915. Term of patent 3½ years.

To all whom it may concern:

Be it known that I, JAMES MADDOCK, a citizen of Great Britain, residing at Alsager, in the county of Chester, England, have invented 5 a new, original, and ornamental Design for a Covered Dish.

In the drawings, Figure 1 is a side view of the design for a covered dish. Fig. 2 is an end view, and Fig. 3 is a top plan view.

What I claim is—
The ornamental design for a covered dish, as shown.

JAMES MADDOCK.
